UNITED STATES PATENT OFFICE.

ARTHUR VON FRANKENBERG, OF NEW YORK, N. Y., ASSIGNOR TO FRANKART, INC., OF NEW YORK, N. Y., A CORPORATION OF NEW YORK.

DESIGN FOR AN ASH TRAY.

Application filed September 15, 1928. Serial No. 28,168. Term of patent 3½ years.

To all whom it may concern:

Be it known that ARTHUR VON FRANKENBERG, a citizen of the United States, and resident of New York city, in the county of New York and State of New York, has invented a new, original, and ornamental Design for an Ash Tray, of which the following is a specification, reference being had to the accompanying drawing, forming part thereof, in which the figure is a perspective view of an ash tray embodying my new design.

I claim:

The ornamental design for an ash tray as shown.

Dated September, 1928.

ARTHUR VON FRANKENBERG.
